METHOD OF MAKING NECKTIES

Jesse E. Langsdorf, New York, N. Y., assignor to
 Cluett, Peabody & Co., Inc., Troy, N. Y., a corporation of New York

Application July 17, 1940, Serial No. 345,897

1 Claim. (Cl. 2—146)

My invention relates generally to neckties and more particularly to an improved necktie construction of the type known as "four-in-hand" and to the method of making the same.

It is well known that in tying four-in-hand neckties certain adjustments must be made during the tying operation if an attractively formed and positioned knot is to be obtained. In order to effect such adjustment, a considerable amount of pulling strain is required on the necktie to form the knot and to overcome the tendency of the collar to frictionally hold the neckband portion of the tie during positioning. In four-in-hand neckties of the type heretofore manufactured, these knotting and pulling strains often resulted in the permanent distortion of the necktie.

Certain attempts have been made to overcome the above described disadvantages. For example, I have disclosed one such attempt in my Patent No. 1,447,090, dated February 27, 1923, in which a resilient lining member was loosely stitched to the tie fabric.

One of the objects of my invention is to provide an improved necktie construction which will form a smooth, attractive knot without distortion of the necktie, and which may be made without the use of a separate lining member.

Another object of my invention is to provide an improved necktie construction of the character described and an improved, relatively inexpensive method of making the same.

Other objects of this invention will in part be obvious and in part hereinafter pointed out.

The invention accordingly consists in the features of construction, combinations of elements, and arrangement of parts hereinafter described, and of which the scope of application will be indicated in the claim.

In the accompanying drawing, in which is shown one of the various possible embodiments of this invention,

Fig. 1 is a view of a necktie fabric blank cut to predetermined shape in accordance with my invention;

Fig. 2 is a view illustrating a step in the making of my improved necktie;

Fig. 3 is a view illustrating still another step in the making of my improved necktie;

Fig. 4 is a rear view of the necktie completed in accordance with my invention;

Fig. 5 is an enlarged cross-sectional view taken substantially on the line 5—5 of Fig. 2;

Fig. 6 is an enlarged cross-sectional view taken substantially on the line 6—6 of Fig. 3; and

Fig. 7 is an enlarged cross-sectional view taken substantially on the line 7—7 of Fig. 4.

Referring now in detail to the drawing, I have disclosed a method of manufacturing a four-in-hand necktie in accordance with my invention.

In Fig. 1 there is shown a suitable necktie fabric blank 10 which has been cut to a predetermined shape and which is cut on the bias so that the bias lines are disposed at angles of substantially 45° to the longitudinal axis of the completed necktie. It is thus seen that the blank 10 will be freely stretchable and resilient to a high degree in a direction along its longitudinal axis. This amount of stretch of the flat blank would ordinarily be more than is desirable in a finished necktie. Therefore, in accordance with my invention, I have provided the following necktie construction which offsets the undue stretchiness.

The fabric blank 10 is preferably made so that the longitudinal edges 11 and 12 are substantially symmetrically disposed with respect to the longitudinal axis of the blank, and the blank 10 is made sufficiently wide to permit longitudinal folding on the fold lines 14—14, 15—15, 16—16, and 17—17. The fold lines 14—14 and 15—15 determine the ultimate width of the finished necktie. It will be noted that the pairs of fold lines 14—14, 15—15, 16—16, and 17—17 are symmetrically disposed with respect to the longitudinal axis of the blank.

A method of making the necktie of my invention will now be described. The fabric blank 10 is herein referred to as a "one-piece blank" to distinguish it from blanks comprising two or more registering plies, but it is to be understood that the blank, as is customary in necktie manufacture, may be made of two separate pieces united by a transverse seam in the neckband portion. This one piece blank is first longitudinally folded in half on its longitudinal axis with the wrong side of the fabric outermost (as shown in Fig. 2). The folded fabric is then sewed together by a line of stitching 18 disposed in substantial alignment with the adjacently disposed subsequent fold lines 16—16 and 17—17 as shown in Figs. 2 and 5 of the drawing. Any suitable means may be employed for stitching, such as for example, by hand or by the use of suitable slip stitching machines of the type disclosed in Reissue Patent No. 19,683, dated July 23, 1935. Preferably loose stitching known as slip stitching is used to preserve the longitudinal resiliency of the completed necktie. By slip-stitching is meant a loose running stitch which is designed to permit the necktie to ex-

tend during the service pull and come back to its original length and dimensions when this service pull is released. The tubular necktie fabric thus formed by the row of stitching 18 may then be flattened out as shown in Figs. 3 and 6 with the line of stitching 18 substantially coinciding with and overlying the longitudinal axis of the tie and the fabric 10 folded on the fold lines 14-14 and 15-15 defining the width of the tie. The adjacently disposed longitudinal edges 11-11 and 12-12 may then be spread apart to flatly overlie the folded fabric.

If desired, the necktie, when properly arranged as shown in Fig. 3, may be pressed to retain its shape and then turned inside out to form the finished necktie shown in Figs. 4 and 7.

The completed necktie shown in Figs. 4 and 7 consists of three flat thicknesses of bias cut fabric. The edges 11 and 12 quite closely approach the creases 15-15 and 14-14 respectively. In tying the necktie the three thicknesses lie uniformly upon each other and are uniformly stretchable and resilient so that an attractive knot is formed without permanent distortion of the necktie and without the exertion of undue pulling forces. The tie may be made of washable fabric and readily washed and repressed at home without displacement of the edges 11 and 12 and without the formation of polished lines on the face of the tie.

Although in my preferred embodiment the tie is provided with three flat thicknesses of fabric substantially throughout its length the extent of the tie which is so constructed may be restricted to the knot tying region and the edges 11 and 12 may be located nearer the longitudinal axis of the tie in other portions if it is desired to reduce the amount of fabric used.

The necktie may also be made with a separate bias cut lining in which event the lining may be secured to the tie by the slip stitching 18 before the tie is turned inside out.

It will thus be seen that there is provided a four-in-hand necktie and an economical and efficient method of making the same in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

I claim:

15 The method of making a four-in-hand necktie from a one-piece fabric blank, comprising the steps of folding said blank substantially in half with the wrong side of the fabric outermost and its longitudinal raw edges substantially in registry, stitching the resultant overlying fabric portions together by a row of stitching which extends longitudinally of the folded blank substantially one-third of the distance between said superimposed longitudinal raw edges and the fold 20 line to thereby form a tubular tie casing, rearranging said casing with the row of stitching uppermost and coinciding with the longitudinal axis of the tie, separating the two flaps formed between the line of stitching and said longitudinal raw edges, flattening the casing in said position to form two edge fold lines and two centrally disposed contiguous fold lines to thereby arrange said flaps to extend respectively in opposite directions from the line of stitching each with a longitudinal raw edge substantially in registry with an edge fold line of the casing, and then turning said casing inside out to thereby place said flaps on the inside of the casing in said pre- 25 arranged relationship.

JESSE E. LANGSDORF.
